DESIGN FOR AN ARTIFICIAL BAIT

Floyd A. Phelps, Paw Paw, Mich., assignor to Paw Paw Bait Company, Paw Paw, Mich., a corporation of Michigan

Application June 3, 1940, Serial No. 92,779

Term of patent 14 years

To all whom it may concern:

Be it known that I, Floyd A. Phelps, a citizen of the United States, residing at Paw Paw, in the county of Van Buren, State of Michigan, have invented a new, original, and ornamental Design for an Artificial Bait, of which the following is a specification, reference being had to the accompanying drawing, forming part thereof.

Figure 1 is a top plan view, with legs extended; Figure 2 a side elevational view, with legs in the position shown in Figure 1; Figure 3 a top plan view, with legs in one collapsed position; Figure 4 a side elevational view with legs in the position shown in Figure 3; Figure 5 a front view, with legs in collapsed position; and Figure 6 a rear view with legs in collapsed position, of an artificial bait showing my new design.

I claim:

The ornamental design for an artificial bait, as shown.

FLOYD A. PHELPS.
